UNITED STATES PATENT OFFICE

2,207,020

APPARATUS FOR ATTACHING SOLES TO SHOES

Clifford K. MacDonald, Brockton, Mass., assignor to United Shoe Machinery Corporation, Borough of Flemington, N. J., a corporation of New Jersey

Application January 17, 1939, Serial No. 251,370

8 Claims. (Cl. 12—33)

This invention relates to improvements in machines for attaching soles to shoes with cement by the application of pressure and is illustrated herein as embodied in an improved apparatus for supporting and pressing a welt or other marginally projecting portion of a shoe against the margin of the sole which extends beyond the last, in opposition to the pressure applied to the outer face of the sole in the sole-attaching operation.

An object of the invention is to provide an improved welt presser which can be conveniently and effectively used in connection with, or can be embodied in, the pressure pad of a cement-sole-attaching machine and which will readily accommodate and support the welts of shoes of a large variety of sizes and shapes. While the illustrated welt presser was developed particularly for use in cement attaching soles to men's shoes with the aid of a cement-sole-attaching machine of the character disclosed in United States Letters Patent No. 2,047,185, granted July 14, 1936, on an application filed in the name of Milton H. Ballard et al., it should be understood that the invention is not limited in its utility to a machine of that type nor is it limited to use in the manufacture of men's shoes.

Features of the invention include an improved, flexible welt presser adapted to be easily and quickly applied and conformed to the welt crease of a shoe resting upon a pressure pad and to be pressed snugly into, and held firmly in, the welt crease of a shoe, to press upon and support the welt during the application of pressure to the sole of the shoe; and a novel form of welt presser comprising an elongated, flexible, tubular, welt-engaging element, preferably of rubber, containing a mass of round, rigid balls, which mass will, under pressure, flow to a certain extent to permit the welt support to conform closely to the welt crease of a shoe and will transmit pressure uniformly to the welt, regardless of the size or shape of the shoe.

A further feature of the invention comprises the combination in an integral unit with a sole-pressing pad, of a welt presser which is conformable to the welt creases of various shoes. In this case, the welt-pressing element may advantageously be hollow, with its interior in communication with the interior of the pressure pad, the whole being filled with a mass of flowable material, preferably the round, rigid balls mentioned above, thus securing a uniform distribution of pressure over the sole and welt.

With the above and other objects and features

in view, the invention will now be described with reference to the accompanying drawings, in which

Fig. 1 is an angular view, illustrating one form of my improved welt presser in combination with a sole-pressing pad;

Fig. 2 is a view partly in cross section of a detail of the welt-engaging element and means for applying pressure thereto;

Fig. 3 is a plan view of a pressure pad combined with a welt presser of a slightly different form, and

Fig. 4 is a view, partly in end elevation and partly in cross section, of the apparatus shown in Fig. 3.

The invention is illustrated herein as applied to a machine of the type disclosed in the above-mentioned Ballard et al. Patent No. 2,047,185 and the levers 314 and 316 correspond to the levers bearing the same reference numerals in said patent, these levers serving, respectively, to apply downward pressure to the heel portion of the last in a shoe 10 and to the forepart of the shoe, to press the shoe down upon the sole-pressing pad 12 which is contained in a pad box 14. The sole and welt of the shoe are designated by 16 and 18, respectively. In this form of the invention, the pad 12 may contain any suitable, flowable, filling material 20, such as water, a mass of round, rigid balls, or any other material capable of supporting the sole-attaching pressure while permitting the pad to conform to the tread surface of the sole.

In accordance with the present invention, there is provided an elongated, U-shaped, flexible, conformable, welt-supporting and pressing element 22, consisting of a tube of rubber, leather or other material equivalent for the purpose. The normal cross-sectional shape of the element 22 is approximately as shown in Fig. 2, having an exterior ridge 110 along one side thereof, in order to minimize the amount of distortion necessary to make it fit exactly in the welt crease of a shoe.

The flexible tube, which is shown at 23, is filled with a mass of small, round, rigid balls 26, which mass flows readily under pressure to conform to the shape of the welt-crease portion of the shoe and distribute the pressure uniformly thereover but when the pressure reaches a certain intensity, forms a fairly rigid pressing surface.

The welt-pressing element 22 may be a detached, portable device which may be applied to the shoe by hand, preparatory to the application of pressure, or it may be supported by and secured to pressure mechanism, one form of which is

illustrated in Figs. 1 and 2. In these figures are shown a front pressure shoe 28 and a rear pressure shoe 30 arranged to engage, and, if desired, to support, the welt presser 22.

5 The front pressure shoe 28 is hung upon a vertically slidable rod 32 by a pivot screw 34 and upon a horizontally slidable bar 36 by a pivot 38. The bar 36 is supported in a guideway disposed transversely of the pad 12 and formed in 10 a block 40 which is adjustable longitudinally of the pad upon a dovetail 42 formed upon a plate 44 secured to the pad box 14.

A pull spring 46 having its ends secured, respectively, to a pin 48 mounted in the bar 36 and 15 a pin 50 mounted in the block 40, tends to draw the bar outward and holds a cam roll 52, journaled in the outer end of the bar, against an eccentric cam 54 having a handle 56, by which it may be moved about a pivot 58 supported in a 20 bracket 60 which constitutes an extension of the block 40. It will be apparent that if the cam 54 is rotated by means of the handle 56, the bar 36 will be forced inward toward the shoe 10, causing the pressure shoe 28 to exert inward pressure 25 upon the shoe 10 through the welt presser 22.

The rear pressure shoe 30 is hung upon a vertically slidable rod 62 and a horizontally slid- 30 able bar 64 in a manner similar to that in which the front pressure shoe 28 is supported.

30 As shown in Fig. 2, the bar 64 is guided in a sleeve 66 which is mounted in a bracket 68 se- 35 cured to the pad box 14 and a pull spring 70, of which one end is attached to a pin 72 fixed in the bar 64 and the other end is attached to a pin 74 fixed in the sleeve 66, tends to draw the bar 64 rearward. The rear pressure shoe 30 is 40 connected to the bar 64 by a pivot 76 and the inner faces of the pressure shoes 28 and 30 are shaped to conform approximately to the contour 45 of the tube 24 which, as above stated, may either be secured to and supported by the pressure shoes or may be entirely separated therefrom, in which case the pressure shoes merely bear upon and apply pressure to the welt-crease-engaging ele- 50 ment. In order to advance the rear pressure shoe 30 against the tension of the spring 74, an up- 55 right arm 78 of a bell crank lever movable about a stationary pivot 80 bears against the outer end of the slidable bar 64. The other arm 82 of the bell crank lever extends forward beneath the pad 50 box and its front end constitutes a handle by which the lever may be actuated to advance the pressure shoe 30 to force the welt-engaging ele- 60 ment 22 into the welt crease of the shoe.

55 The rods 32, 62 are supported for vertical movement in guides 84, 86 carried by a stationary bracket 88, in an overhanging portion 90 of which is journaled a cross screw 92. Endwise motion of the screw 92 is prevented by collars 94, 96 65 secured to the screw and handles 98 provide for manual rotation of the screw.

65 The screw 92 is threaded very loosely through a transverse equalizing bar 100 in which is formed a groove 102. The upper ends of the rods 32, 62 are rounded, as shown at 104, and are received loosely in the groove 102. Each of 70 said rods is supported by a pull spring 106 having sufficient tension to carry the weight of the rod and the parts supported thereby. When the screw 92 is turned to lower the equalizer 100, the latter will force the rods 32, 62 downward and thus apply downward pressure upon the welt of the shoe 10.

At 108 is shown one of the regular sole-posi-

tioning fingers of the sole-attaching machine, by which the sole 16 is positioned upon the pad 12 before the shoe is placed upon it.

Although the ridge formation, shown at 110, 5 is not essential, it is preferred because it facilitates the establishment of close contact between the welt presser 22 and the shoe parts in the welt crease of the shoe.

In the form of the invention illustrated in Figs. 3 and 4, the pressure pad is shown at 112 10 and the pad box at 114. In this case, the filling of the pad consists preferably of a mass of small, round, rigid balls 120. Integral with the top of the pad, which may advantageously be made of rubber, is formed an elongated, hollow, 15 flexible, welt-pressing member 122, the interior of which is in communication with the interior of the pad and is filled with part of the balls of the mass 120 in the pad. A pair of pressure shoes 124, 126 is arranged to press inward and down- 20 ward upon the welt-pressing element 122, causing the latter to roll inward over the edge of the sole and to press inward against the shoe and downward upon the surface of the welt.

The pressure shoes 124, 126 are pivoted, re- 25 spectively, at 128, 130 upon the upper ends of a pair of levers 132, 134 movable about stationary pivots 136, 138. The lower ends of the levers 132, 134 are drawn toward each other by a pull spring 140 and carry antifriction rolls 142, 144 30 which are engaged by a wedge member 146 connected by a rod 148 to a treadle 150 normally elevated by a spring 152. The upward limit of movement of the treadle 150 and, consequently, the separation of the upper ends of the levers 132, 35 134 is adjustably determined by a stop screw 154.

The pressure shoes 124, 126 are provided with tail portions 156, 158 which bear upon the upper 40 surface of the pad 16 and cause the pressure shoes to be rocked about their pivots when the levers 132, 134 are moved inward toward each other.

In order to increase the downward component of the pressure applied by the pressure shoes, there are provided bell crank levers 160, 162 which are movable about stationary pivots 164 45 and 166, respectively. The arms 168, 170 of these bell crank levers carry rolls 172, 174 which engage surfaces 176 and 178 formed upon the upper portions of the levers 132, 134.

Engaging the inner sides of the arms 168, 170 50 are rolls 180, 182 carried in the upper ends of levers 184, 186 which are connected by short springs to the bell crank lever arms 168, 170. The levers 184, 186 are movable about stationary pivots 188, 190 and their lower ends are formed 55 at 192, 194 to be engaged by screws 196, 198 which are adjustably threaded through the levers 132, 134.

The other arms 200, 202 of the bell crank levers 160, 162 carry at their lower ends anti- 60 friction rolls 204, 206 arranged to engage the top faces of the pressure shoes 124, 126 when said shoes have been swung inward and the bell crank levers have been swung outward. Springs 205, 207 tend to swing the bell crank levers in- 65 ward to the positions illustrated in Fig. 4.

In the operation of this form of the invention, the sole 16 and the shoe 10 are positioned upon the pad 112 and the treadle 150 is depressed. As the wedge 146 swings the levers 132, 134 so 70 that their upper ends are moved toward each other, the pressure shoes 124, 126 move inward and rock about their pivots, forcing the welt-pressing element 122 into the welt crease of the shoe 10. The points of the screws 196, 198 75

engage the faces 192, 194 and swing the upper ends of the levers 184, 186 outward, causing the rolls 204, 206 to be moved in above the pressure shoes 124, 126 and to force the latter downward to press the element 122 firmly down upon the welt 18. When the rolls 172, 174 pass the lines joining the centers of the pivots 136, 164 and 138, 166, respectively, they no longer exert any tendency to swing the bell crank levers 160, 162 back to their initial positions and no great amount of pressure upon the treadle 150 is required to maintain the pressure upon the welt while the sole-attaching pressure is applied by the machine. Any increase in the pressure of the shoe upon the pad will, by reason of the flow of the balls 120, cause a corresponding increase in the pressure of the element 122 upon the welt, thus insuring a uniform application of pressure throughout.

Having described the invention, what is claimed as new and desired to be secured by Letters Patent of the United States is:

1. A welt presser comprising a hollow, elongated, U-shaped, flexible member adapted to fit in the welt crease of a shoe and containing a mass of round, rigid balls.

2. A welt presser comprising a hollow, elongated, U-shaped, flexible tube having a protruding ridge along the inner side thereof and containing a mass of round, rigid balls.

3. Welt-pressing apparatus comprising, in combination, a hollow, flexible, welt-engaging member which is filled with a mass of round, rigid balls and is conformable to the welt crease of a shoe, and means for forcing said member into said welt crease.

4. Welt-pressing apparatus comprising, in combination, a hollow, flexible, welt-engaging member filled with a flowable mass of rigid balls, a presser shoe constructed and arranged to en-

gage the outside of said member when the latter is disposed in the welt crease of a shoe, and manually operable means for moving the presser shoe toward said shoe to force the welt-engaging member snugly into the welt crease thereof.

5. A sole-attaching apparatus comprising a flexible pressure pad constructed and arranged to engage the tread face of the sole of a shoe, a flexible welt-engaging and pressing member integral with said pad, and means for forcing said member into conformity with the welt crease of a shoe upon the pad.

6. A sole-attaching apparatus comprising a hollow pressure pad constructed and arranged to engage the tread face of the sole of a shoe, a hollow welt-engaging and pressing member arranged with its interior in communication with the exterior of the pad, and a single mass of flowable material filling both the pad and the welt-pressing member.

7. A sole-attaching apparatus comprising a pressure pad constructed and arranged to engage the tread face of the sole of a shoe, a flexible welt-engaging and pressing member fast upon the surface of the pad and means for rolling said welt-pressing member over the edge of the sole and into pressing contact with the surface of the welt.

8. Welt-pressing apparatus comprising, in combination, a pressure pad filled with a flowable mass of rigid balls and constructed and arranged to engage the sole of a shoe, a welt-engaging and pressing member disposed above the surface of the pad and also filled with a flowable mass of rigid balls, and means for forcing said welt-engaging member inward against a shoe upon the pad and downward against the welt of the shoe.

CLIFFORD K. MACDONALD. 40
